UNITED STATES PATENT OFFICE.

EARL EDGAR GINTER, OF RANSHAW, PENNSYLVANIA.

COMBINED COMPASS AND PROTRACTOR.

Application filed May 5, 1925. Serial No. 28,135.

To all whom it may concern:

Be it known that I, EARL E. GINTER, a citizen of the United States, residing at Ranshaw, in the county of Northumberland and State of Pennsylvania, have invented certain new and useful Improvements in Combined Compasses and Protractors, of which the following is a specification.

The present invention relates to a combined compass and protractor, and has for its principal object to provide a device which is efficient and reliable in measuring angles, and will be particularly useful to such persons as draftsmen, engineers, carpenters, etc.

The invention contemplates the provision of an exceedingly simple structure which may be placed on the market at a relatively low cost, and one which is not likely to easily become out of order, is strong, durable, light, compact, and otherwise well adapted to the purpose for which it is designed.

With the above and numerous other objects in view, as will appear as the description proceeds, the invention resides in certain novel features of construction, and in the combination and arrangement of parts as will be hereinafter more fully described and claimed.

In the drawing:

Figure 1 is a side elevation of the device embodying the features of my invention.

Figure 2 is a fragmentary detail section on an enlarged scale, taken through an intermediate portion of one leg, of the device.

Figure 3 is a section similar to that shown in Figure 2, but being taken at right angles thereto, and

Figure 4 is a fragmentary enlarged detail section through the free end of the leg shown in Figures 2 and 3.

Referring to the drawing in detail, it will be seen that numerals 1 and 2 designate the legs of the combined compass and protractor which are pivoted together, as at 3, and the lower ends thereof terminate in points as at 4.

The leg 2 is of a tubular formation and has a drum 5 formed in an intermediate portion thereof. The axis of the drum is disposed at right angles to the axis of the tubular leg 2. One end of the drum 5 is closed, as at 6, while the other end is provided with a detachable closure 7. A shaft 8 is journaled between the closures 6 and 7 and is disposed co-axially with the drum 5. The drum 5 is provided with a window 9.

A disc 10 is fixed to the shaft 8 and provided with an annular flange or rim 11, which is adapted to move over the window 9 and has on its exterior surface suitable indicating indicia, which may be seen through the window 9 for a purpose to be brought out later. A shaft 12 is journaled through the bottom portion of the drum and extends downwardly through the leg 2 co-axially therewith, and terminates adjacent a slot 13 provided in the leg 2 adjacent its point 4. An arm 14 is pivoted on the lower extremity of the shaft 12 and when swung about the axis of the leg 2 imparts rotary motion to the shaft 12. A needle 15 is pivoted on the end of the arm 14. A bevelled gear 16 is fixed to the upper end of the shaft 12 and meshes with a bevelled gear 17 fixed to the shaft 8. A coil spring 18 is disposed about the shaft 8 and has one end fixed to the disc 10 and the other end fixed to the closure 6. An arcuate rod 19 is fixed to the leg 2 and extends through a slot 20 in the leg 1, so that the legs 1 and 2 may be held in different adjusted angular positions in relation to each other, by the binding screw 21 in the leg 1 engaging the rod 19. This rod 19 may be provided with suitable indicia so as to indicate the angle between the legs 1 and 2.

In using this device, the point 4 of the leg 2 is placed at the vertex of the angle and the needle 15 engaged with one side of the angle. The point 4 of the leg 1 is then moved so as to engage the other leg of the angle. As the leg 1 is swung so as to engage the other leg of the angle, the tubular leg 2 is revolved about the shaft 12, thereby causing the rotation of the gear 16 since it moves in an orbit about the axis of the shaft 12, and since it is in mesh with the gear 17, said gear 17 will rotate, thereby rotating the shaft 8, the disc 10, and the rim 11, so as to tension the spring 18. The indicia read through the window 9 will designate the angle in degrees or any other suitable measuring unit. A stop 23 is provided in the drum 5 and is engageable by a lug 24 extending from the rim 11. The spring 18 normally holds the rim at a zero indicating position and likewise holds the arm 14 and legs 1 and 2 in the same plane.

It is thought that the construction, operation, utility, and advantages of the invention will now be clearly understood without a more detailed description. It is desired, however, to point out that numerous

changes in the details of construction, and in the combination and arrangement of parts may be resorted to without departing from the spirit or scope of the invention as hereinafter claimed or sacrificing any of its advantages.

Having thus described my invention, what I claim as new is:

1. A device of the class described including a pair of legs pivoted together, an arm extending from one of the legs, means associated with said arm for engaging one side of an angle, and an indicating mechanism operatively associated with the arm so that when the other leg is engaged with the other side of the angle, said indicating mechanism will be brought into play to indicate the size of said angle.
2. In a device, a pair of pivotally associated legs, one of said legs being tubular, a shaft journaled longitudinally of the tubular leg, said tubular leg provided with a slot adjacent the terminal of the shaft, an arm pivoted to said terminal of the shaft and adapted to swing through the slot, an engaging member on the arm, an indicating mechanism, and means operatively connecting the shaft and the indicating mechanism.
3. In a device of the class described, a pair of legs pivoted together at adjacent ends, one of said legs being tubular and provided with a drum formed intermediate its ends, said drum provided with a window, a shaft journaled in the drum, an indicator

mounted on the shaft, so as to be read through the window, a gear on the shaft, a second shaft journaled through the drum and longitudinally of the tubular leg and provided with a gear at one end meshing with the first mentioned gear, said tubular member provided with a slot adjacent the end of the second shaft, an arm extending through the slot and pivoted to the adjacent end of the second shaft, an engaging member on the arm.

4. In a device of the class described, a pair of legs pivoted together at adjacent ends, one of said legs being tubular and provided with a drum formed intermediate its ends, said drum provided with a window, a shaft journaled in the drum, an indicator mounted on the shaft, so as to be read through the window, a gear on the shaft, a second shaft journaled through the drum and longitudinally of the tubular leg and provided with a gear at one end meshing with the first mentioned gear, said tubular member provided with a slot adjacent the end of the second shaft, an arm extending through the slot and pivoted to the adjacent end of the second shaft, an engaging member on the arm, and a spring associated with the shaft for holding the arm in substantially the same plane with the legs and the indicating device at a zero indicating position.

In testimony whereof I affix my signature.
EARL EDGAR GINTER.
